UNITED STATES PATENT OFFICE

167,511

LADY'S STOCKING

Melvin J. Gordon, Brookline, Mass.

Application January 10, 1950, Serial No. 7,135

Term of patent 14 years

(Cl. D47—7)

To all whom it may concern:

Be it known that I, Melvin J. Gordon, a citizen of the United States, residing at 55 Lee Street, Brookline, Massachusetts, have invented a new, original, and ornamental Design for a Lady's Stocking, of which the following is a specification, reference being had to the accompanying drawings, forming a part thereof, in which:

The other side of the lady's stocking is like the side shown.

I claim:

The ornamental design for a lady's stocking, as shown and described.

MELVIN J. GORDON.
